UNITED STATES PATENT OFFICE.

THOMAS J. HAWKINS, OF GUTHRIE, KENTUCKY.

PORTABLE STOCK-YARD.

1,187,990.

Specification of Letters Patent. Patented June 20, 1916.

Application filed March 26, 1913. Serial No. 756,931.

To all whom it may concern:

Be it known that I, THOMAS J. HAWKINS, a citizen of the United States, residing at Guthrie, in the county of Todd and State of Kentucky, have invented new and useful Improvements in Portable Stock-Yards, of which the following is a specification.

This invention relates to improvements in building construction and has for its object 20 to provide improved means of connecting a plurality of sections of a partition wall.

In carrying out my invention use is made of novel locking means for connecting together a number of wall plates which are 15 adapted together to form a continuous partition or siding of a building structure, and to this end my improvement is directed to a knock down structure which consists of a minimum number of parts, which can be 20 set up and assembled with all of its constituent parts by any person without skill, and admits of being readily disconnected without considerable trouble and annoyance.

With the above and other objects in view, 25 my invention consists in the combination, arrangement and details of construction disclosed in the drawing and specification, and more particularly pointed out in the appended claim.

30 In the drawing:—Figure 1 is a fragmentary side elevation of adjacent like sections, the same being partly in section, Fig. 2 is a similar view showing a novel form of lock, Fig. 3 is a front elevation, partly in section, of the knock down sections in assembled position, and Fig. 4 is a fragmentary view of a section of a partition taken at right angles to 35 Fig. 3.

Referring to the drawings which are 40 merely illustrative of my invention, a plurality of knock down sections which may be called center sections 21 are adapted to be connected by means now to be explained. Each of these sections is formed from parallel rails or angle uprights 23 in such a manner that the meeting edges of adjacent uprights 23 are connected together by means of locks 24. Each of these locks consists of a bolt passing through one side of the angle 45 iron upright of a section of a partition wall, and having a head 26 abutting the same and the bolt is also provided with an enlarged body portion 27 while one side of the angle iron upright of an adjacent section is provided with an opening 28 of a greater length 55

than the length of said body portion 27, and through this opening the body portion is adapted to project so as to rest upon the lower edge 29 of said opening and to be spaced apart from the upper edge 30 of said opening. In this way the withdrawal of the bolt from the slot is effectively prevented. There is an arm 31 pivoted upon the side of each angle iron upright which is formed with the said opening 28, the function of which is to force the body portion of the lock to occupy a position so as to prevent the body portion engaging the upper edge of the opening. This is accomplished, by causing the free end of said arm 31 to engage the upper end of the body portion thereby locking it against reverse movement. Besides the body portion of this lock may have a tendency to withdraw the hook bill 32 which engages the angle iron of the upright against which the head of the bolt bears as clearly shown in Fig. 2.

It will be seen from the foregoing explanation that the knock down sections are connected by means of locks in such a manner 40 that, in order that the sections may have their angle iron uprights contacting so as to be suitably connected, one section is slightly raised above the other section so as to enable the body portion of the locking bolt to pass through the opening formed in the opposite section and when this has been done the first section is brought down to a common level with the other section until the body portion of the bolt rests upon the lower edge of the opening and will engage the lock only when the body portion is being initially introduced. The pivotal arm is pressed with its free ends against said body portion to prevent either section being 45 raised relatively to the other. When the pivotal arm is removed from contact with the bolt the sections may be raised and moved in a manner which will be understood.

It is intended to claim all reasonable modifications coming within the view of the structure claimed.

I claim—

A partition wall formed of a plurality of 50 adjoining sections, each section comprising an angle iron frame, one leg of the angle iron forming the edge of the section and the other leg extending inwardly, one vertical edge of each section having secured thereon 55

a locking bolt having a neck and an enlarged head, the abutting edge of the adjacent section having a slot through which the enlarged head passes and into which the neck of the locking bolt extends, said last mentioned angle iron edge having pivoted on its inner face an arm which engages the head of the locking bolt when the sections are in position and forces the neck of said bolt to

the end of the slot, thereby preventing the 10 withdrawal of the bolt from the slot.

In testimony whereof I affix my signature in presence of two witnesses.

THOMAS J. HAWKINS.
